INVENTOR

UNITED STATES PATENT OFFICE.

JOHN W. SUTTON, OF NEW YORK, N. Y.

MACHINE FOR WAXING OR VARNISHING PAPER.

SPECIFICATION forming part of Letters Patent No. 232,777, dated September 28, 1880.

Application filed August 17, 1880. (No model.)

To all whom it may concern:

Be it known that I, JOHN W. SUTTON, of the city, county, and State of New York, have invented certain new and useful Improvements 5 in Machines for Waxing or Varnishing Paper or other Analogous Material; and I do declare that the following is a clear, full, and exact description thereof, reference being had to the accompanying drawings, which form a 10 part of this specification.

My invention relates to the method and means employed for waxing, varnishing, and polishing paper or other fibrous or textile material.

15 The object I have in view is to provide a means whereby paper or other analogous material can be covered and saturated with wax, paraffine, or covered with quick-drying varnishes or paints.

20 My improvement consists in heating the paper or other material subsequent to its delivery from the reel or other form of package, prior to its coming in contact with melted wax, paraffine, or other finishing material, and 25 in continuing and retaining the heat about the coated material a suitable distance and length of time after leaving the point of contact with said coating material, and also in applying the heat to the same side of the material while in 30 transit through the apparatus.

Figure 1 represents a vertical longitudinal section of the apparatus for coating the surface of paper or other analogous material. Fig. 2 represents a top plan of the same.

35 C represents the frame-work of the apparatus. G and G' are reels for letting off and taking up paper or other material while passing through the apparatus. i i represent the material in transit. e e are friction guide-rolls 40 which support the material. D D are pipes, connected with each other by means of headers or return-bends, for the purpose of conducting hot liquids, steam, or heated gases, whereby a suitable degree of heat can be 45 maintained for keeping the coating material in a proper condition to flow over the surface of the substance to be coated, and to assist in drying the same prior to its being taken up by reel G'.

50 E and F represent a case or covering which

surrounds the heating device and guide-rolls, for the purpose of deflecting and retaining the heat about the material which is to be and has been coated while on its way through said inclosure.

A represents the tank or receiver for holding the coating material. a are pipes for conducting heat to said material. h is a bar which contains a series of spigots or plugs which fit into a corresponding number of orifices on the bottom of the tank. When the coating material is to be discharged the bar is raised and regulated by the screw h, after which the melted material will drip down into the apron c, and thence flow down beneath the heated pipe B and escape through the perforations in the apron beneath the heated pipe B, thence with the moving paper or other material. e' e' represent pulleys for turning the guide-rolls.

55 The operation of my invention is as follows: The paper is passed from reel G over roll e', thence beneath a series of heating-pipes, D', which heat the paper to a suitable degree prior to its coming in contact with the melted wax or paraffine. This is done for the purpose 60 of driving off any moisture that may be in the paper, and to allow the melted wax or paraffine to penetrate quickly and diffuse itself through every part of the paper. After 65 the paper is filled with the heated wax it is kept hot by passing it beneath a series of heated pipes or beneath a heated surface, but not in contact therewith. This continued heating is for the purpose of keeping the wax 70 or paraffine melted, so that it will flow evenly over the surface of the paper, and present after leaving the apparatus a polished surface, or a surface analogous to a coat of varnish 75 when flowed on the work and allowed to dry. 80 The flow-surface must not come in contact with the pipes or other heating-surface, as they would abrade the surface while in transit.

85 The roll G' should be so far removed from the heating device that the wax or paraffine 90 will have time to cool prior to its being taken up on the reel.

95 The quantity of wax or paraffine can be graduated by the speed of the paper or by the discharge from the tank.

100

The moving parts of this apparatus can be driven by power obtained from mechanical contrivance, or by hand-power.

What I claim, and desire to secure by Letters Patent, is—

1. In an apparatus for preparing waxed paper, the combination of a tank in which the wax is melted, apron *c*, and pipe *B*, the heating device *D'* for heating the paper prior to its passage beneath the apron *c* and heating-

pipe *B*.

2. In an apparatus for waxing or varnishing paper or other fibrous or textile material, the combination of a device for distributing melted

wax, paraffine, or other similar substance or substances which are liquid, but dry quickly when spread out in thin coats, and a heating device for heating the material to be coated prior to its contact with the melted or liquid substance, and the heating device for heating and causing the melted or liquid substance to flow and dry while passing through the apparatus.

JOHN W. SUTTON.
